US00D762818S

(12) **United States Design Patent**
Kline

(10) **Patent No.:** **US D762,818 S**
(45) **Date of Patent:** **** Aug. 2, 2016**

(54) **MIXING VALVE BODY**

(71) Applicant: **Magarl, LLC**, Naples, FL (US)

(72) Inventor: **Kevin B. Kline**, Whitefish Bay, WI (US)

(73) Assignee: **Magarl, LLC**, Naples, FL (US)

(**) Term: **15 Years**

(21) Appl. No.: **29/527,118**

(22) Filed: **May 15, 2015**

Related U.S. Application Data

(60) Continuation of application No. 14/076,552, filed on Nov. 11, 2013, now Pat. No. 9,218,006, which is a continuation of application No. 13/221,376, filed on Aug. 30, 2011, now Pat. No. 8,579,206, which is a continuation of application No. 11/676,432, filed on Feb. 19, 2007, now abandoned, which is a continuation of application No. 10/939,585, filed on Sep. 13, 2004, now Pat. No. 7,191,954, which is a continuation of application No. 10/378,185, filed on Mar. 3, 2003, now Pat. No. 6,851,440, which is a continuation of application No. 09/941,141, filed on Aug. 28, 2001, now Pat. No. 6,543,478, which is a division of application No. 09/633,728, filed on Aug. 7, 2000, now Pat. No. 6,315,210, which is a continuation of application No. 09/165,880, filed on Oct. 2, 1998, now abandoned.

(57) **CLAIM**

The ornamental design for a mixing valve body, as shown and described.

DESCRIPTION

FIG. 1 is a perspective view of a mixing valve body according to one embodiment of the present invention; and, FIG. 2 is a front view of the apparatus of FIG. 1.

The rear, bottom, and left side views of the mixing valve body are not part of the claimed design.

1 Claim, 2 Drawing Sheets
